UNITED STATES PATENT OFFICE.

GEORGE P. WIGGINTON AND FRANK W. HODGES, OF KALAMAZOO, MICHIGAN,
ASSIGNORS TO KALAMAZOO LOOSE LEAF BINDER COMPANY, OF KALAMAZOO,
MICHIGAN.

TEMPORARY BINDER OR LOOSE-LEAF HOLDER.

979,622.

Specification of Letters Patent. Patented Dec. 27, 1910.

Application filed February 28, 1910. Serial No. 546,558.

To all whom it may concern:

Be it known that we, GEORGE P. WIGGINTON and FRANK W. HODGES, citizens of the United States, residing at Kalamazoo, Michigan, have invented certain new and useful Improvements in Temporary Binders or Loose-Leaf Holders, of which the following is a specification.

This invention relates to improvements in temporary binders or loose leaf holders.

The main objects of our invention are, first, to provide an improved temporary binder or loose sheet holder that may be rapidly manipulated to permit the insertion or the removal of the sheets or leaves. Second, to provide in a temporary binder or loose sheet holder an improved means for adjustably securing the binding cords. Third, to provide an improved temporary binder or loose sheet holder which is very simple and economical in structure.

Further objects and objects relating to structural details will definitely appear from the detailed description to follow.

25. We accomplish the objects of our invention by the devices and means described in the following specification.

The structure described constitutes one effective embodiment of our invention. Other 30 embodiments would be readily devised by those skilled in the art.

The invention is clearly defined and pointed out in the claims.

A structure constituting an effective and 35 preferred embodiment of the features of our invention is clearly illustrated in the accompanying drawing, forming a part of this specification, in which:

Figure 1 is a detail inside plan of a structure embodying the features of our invention, the sheets or leaves being indicated in conventional form therein. Fig. 2 is an enlarged detail longitudinal section taken on a line corresponding to line 2-2 of Fig. 1. Fig. 3 is an enlarged detail section taken on a line corresponding to line 3-3 of Fig. 1, showing details of the binding cord securing means. Fig. 4 is an enlarged detail section taken on a line corresponding to line 4-4 of Fig. 1.

In the drawing similar reference characters refer to similar parts throughout the several views and the sectional views are taken looking in the direction of the little 55 arrows at the ends of the section lines.

Referring to the drawing, we illustrate our invention as applied to a binder having a pair of covers 1 and 2, the cover 1 being provided with a chamber or cavity 3 to receive the mechanism for adjustably securing the binding cords 4. The binding cords here illustrated are in the shape of flat thongs, and are secured to the cover 2 by engaging over the pins or studs 5, the binding cords being provided with suitable holes 6 to engage the studs or pins. Above these studs or pins, the covers are provided with openings 6, so that the cords can be easily adjusted over the pins. We preferably provide in this connection clamping bars 7 between which the leaves or sheets are clamped. The clamping bars illustrated are formed of strips of sheet metal, having bead-like rolls 9 on their rear edges, which make the clamping bars rigid, and also serve as bearings for the inner curved ends 10 of the cover. See Fig. 2. Reinforcing strips 11 are preferably provided for the clamping bars. These reinforcing strips are in the form of flat strips of metal which are suitably secured to the binding strips, the edges of the bead 9 being preferably clamped upon the same. The holes 12 in the clamping bars are arranged relative to the holes 13 in the ends of the cover, so that the clamping bars may 85 move relative to the covers, or the covers relative to the clamping bars in the opening and closing of the book, without varying the tension on the binding cords.

The binding cords are adjustably secured to the cover 1 by the securing means consisting of a spring or yielding bar 14. This bar is preferably provided with inwardly-facing teeth and secured at its ends to the outer wall of the cover, being arranged within the cover chamber 3. Slidably associated with this bar is a binding cord member 15, the member being arranged to slide on the outer chamber wall, and being provided with outwardly-facing bar-engaging members 16. The binding cords are preferably secured to this member by means of the cross bar 17 which is mounted thereon.

The inner wall 18 of the cover 1 is provided with a slot 19 through which the clamping lever 20 may be manipulated. This lever 20 is mounted by means of the pivots 21 on the binding cord member so that the end 22 of the lever may be engaged with the bar between the bar-engaging mem- 110

bers 15 to force the bar into engagement therewith. See Fig. 2. To insure the disengagement of the bar and the binding cord member when the lever is actuated to release 5 the same, we provide a spring 23. This is, in the structure illustrated, a bowed spring arranged between the bar-engaging member 16 and the binding cord member, so that the bowed portion thereof bears against the bar, 10 disengaging the members when the clamping lever is released.

By arranging the parts as we have illustrated and described, we secure a simple and effective means of securing the binding cords. 15 The structure is simple and economical to produce, and is capable of very rapid manipulation.

Having thus described our invention, what we claim as new and desire to secure by Letters Patent, is:

1. In a structure of the class described, the combination with the cover, of a binding cord; an inwardly-facing toothed spring bar mounted on said cover; a binding cord member 25 slidably associated with said bar, said binding cord member being provided with a pair of outwardly-facing bar-engaging members; an engaging lever mounted on said binding cord member to engage said bar between said bar-engaging members; and a bowed spring arranged in said binding cord member between its said rack engaging members to hold said bar normally out of engagement therewith.

35 2. In a structure of the class described, the combination with the cover, of a binding cord; a toothed spring bar mounted on said cover; a binding cord member slidably associated with said bar, said binding cord member being provided with a pair of bar-engaging members; an engaging lever mounted on said binding cord member to engage said bar between said bar-engaging members; and a bowed spring arranged in said binding cord member between its said rack engaging members to hold said bar normally 40 out of engagement therewith.

3. In a structure of the class described, the combination with the cover, of a binding 50 cord; an inwardly-facing toothed spring bar mounted on said cover; a binding cord member slidably associated with said bar, said binding cord member being provided with a pair of outwardly-facing bar-engaging members; and an engaging lever mounted on said binding cord member to engage said bar between said bar-engaging members.

4. In a structure of the class described, the combination with the cover, of a binding 55 cord; a toothed spring bar mounted on said cover; a binding cord member slidably associated with said bar, said binding cord member being provided with a pair of bar-en-

gaging members; and an engaging lever mounted on said binding cord member to 60 engage said bar between said bar-engaging members.

5. In a structure of the class described, the combination with the cover, of a binding cord; a yielding toothed bar mounted on 70 said cover; a binding cord member slidably associated with said bar, said binding cord member being provided with a bar-engaging member; a bar clamping member mounted on said binding cord member; and a spring 75 carried by said binding cord member arranged to hold said bar normally out of engagement therewith.

6. In a structure of the class described, the combination with the cover, of a binding cord; a yielding toothed bar mounted on 80 said cover; a binding cord member slidably associated with said bar, said binding cord member being provided with a bar-engaging member; and a bar clamping member mounted on said binding cord member.

7. In a structure of the class described, the combination with the cover, of a binding cord; a yielding bar mounted on said 90 cover; a binding cord member slidably associated with said bar; a bar clamping member mounted on said binding cord member; and a spring carried by said binding cord member arranged to hold said bar normally 95 out of engagement therewith.

8. In a structure of the class described, the combination with the cover, of a binding cord; a yielding bar mounted on said cover; a binding cord member slidably associated with said bar; and a bar clamping member 100 mounted on said binding cord member.

9. The combination with the covers, of clamping bars formed of metal strips having out-turned beads on their rear edges, the inner ends of said covers being arranged 105 to bear against said beads on said clamping bars, reinforcing strips therefor, the edges of said beads being clamped thereagainst; and binding cords arranged to connect said covers independently of said clamping bars. 110

10. The combination with the covers, of clamping bars formed of metal strips having out-turned beads on their rear edges, the inner ends of said covers being arranged to bear against said beads on said clamping 115 bars; and binding cords arranged to connect said covers independently of said clamping bars.

In witness whereof, we have hereunto set our hands and seals in the presence of two 120 witnesses.

GEORGE P. WIGGINTON. [I. S.]
FRANK W. HODGES. [I. S.]
